[57] CLAIM

The ornamental design for a golf exerciser, as shown and described.

DESCRIPTION

FIG. 1 is a front view of a golf exerciser.

FIG. 2 is an exploded view thereof; and,
FIG. 3 is an exploded front view of a second embodiment of the golf exerciser.

The broken line shown is for illustrative purposes only and forms no part of the claimed design. The surfaces or portions of the article not shown in the drawings or described in the specification form no part of the claimed design.
